DRAWING HOLLOW ARTICLES

Application filed September 20, 1929. Serial No. 394,119.

This invention relates to the manufacture of shaped articles from sheets of magnesium and magnesium alloys, and is more particularly concerned with the application of the art known as embossing or drawing, i. e. forming hollow articles of a predetermined shape and size, from this metal and its alloys. It is however not limited to manufactures of this kind, but is applicable to all deforming operations on sheets of these metals, which involve a plastic deformation without a noticeable alteration of thickness.

It is generally recognized that the manufacture of hollow articles from metallic sheets by embossing or drawing requires a metal which is ductile to a high degree, and which, therefore, must possess a high elongation. Although the elongation of technically pure magnesium and of quite a number of magnesium alloys, in the form of sheets, when subjected to the usual tensile strength tests exceeds 15 percent, it has been found practically impossible to draw hollow articles from such sheets in the cold state, as they

25 prematurely tear under the stress.

An investigation of the reasons for this remarkable phenomenon shows that in magnesium and magnesium alloy sheets the transverse properties are of such a nature and are so related to the longitudinal properties that in drawing operations the ultimate transverse strength of the metal sheet is exceeded before it is possible to place sufficient work in the metal to produce a definite deformation of the sheet. Therefore, before the drawing operation can produce deformation by elongation in the magnesium or magnesium alloy sheet, the sheet fails because its transverse strength is exceeded.

40 It appears that, with other metals, the ratio between longitudinal and transverse tensions is immaterial with respect to the drawing of sheets in this manner as in that case the longitudinal stresses brought to bear upon the metal generally effect the deformation de-

sired before the ultimate transverse strength limit is attained.

We have now further found that, with a rise in temperature, the transverse and the longitudinal properties change in a decidedly different degree. It finally was discovered that there exists a range of temperature in the case of technically pure magnesium, which, moreover, may be hardened by the addition of limited amounts of zinc and/or aluminum, and/or manganese—in which the transverse strength (K_t) equals or exceeds the longitudinal strength limit (K_l). When working in this temperature range, hollow articles may be produced from magnesium and these magnesium alloys, by drawing, without serious difficulty.

The following table represents, for various temperatures (column 1), corresponding values for the ratio K_t/K_l (column 2) and for the Erichsen indentation values in mm. (column 3), in the case of an alloy consisting of 6.5% Al, 1% Zn, and traces of manganese (about 0.3 percent), balance magnesium.

Temperature	$\frac{K_t}{K_l}$	Erichsen values mm.
20°	0.48	2.0
100°	0.50	2.2
200°	0.85	6.7
300°	1.10	10.0

According to our present invention we therefore draw magnesium and its alloys to hollow bodies in the usual manner within the temperature range, in which the ratio

$$\frac{K_t}{K_l}$$

45 equals or exceeds 1. In the particular case represented, the minimum temperature required thus amounts to about 270° C. and is, in practice, preferably maintained at 350° C.

As mentioned above, we have further sub-

- jected sheets of a number of other alloys of magnesium, especially those containing limited amounts of aluminum and/or zinc and/or manganese, to drawing and have found that the range of temperatures, within which the drawing should be performed, is about the same as in the case of the alloy specifically mentioned above. Among the alloys tested the following particularly lend themselves to drawing in the form of sheets:
- About 1.5-2.2% manganese, balance magnesium.
- About 3.0% Zn, balance magnesium.
- About 3.0% Zn, 2% Al, balance magnesium.
- In the last two alloys, as well as in the alloy containing 6.5% Al and 1% Zn already mentioned, small percentages of manganese (from 0.2 to 1.5 percent) may be present, which tend to diminish their liability to corrode without noticeably influencing their plasticity.
- So as to further facilitate the drawing operation by relieving the material to be drawn of at least part of the strain set up by the friction of the die, we preferably back off the edge of the outer or receiving die in the manner exemplified by the accompanying drawing.
- In this drawing, of which Fig. 1 is an elevation and Fig. 2 a ground plan, 1 indicates the receiving or outer die, 2 the inner die backed off at 3, the edge of the die being indicated by 4.
- To further diminish the friction the usual lubricants as grease, oil, graphite, etc., may be employed in addition.
- We have further found that it is rather essential to heat the dies to a temperature which causes a thermal flow from the dies to the workpiece, so as to maintain the temperature of the latter during the operation. Preferably therefore, the tools are heated to about 50 to 100° C. above the actual drawing temperature and maintained at this temperature during the drawing operation.
- We claim:
1. The method of drawing hollow articles from sheets of magnesium and magnesium alloys which comprises drawing the sheets within a temperature range in which the transverse strength exceeds the longitudinal strength limit of the sheet.
  2. The method of drawing hollow articles from sheets of magnesium and magnesium alloys which comprises drawing the sheets at a temperature amounting to at least 270° C.
  3. The method of drawing hollow articles from sheets of magnesium and magnesium alloys which comprises drawing the sheets at a temperature of about 350° C.
  4. The method of drawing hollow articles from sheets of magnesium and magnesium alloys which comprises drawing the sheets at a temperature amounting to at least 270° C.

with dies heated moderately above the drawing temperature.

5. The method of drawing hollow articles from sheets of magnesium and magnesium alloys which comprises drawing the sheets at a temperature of about 350° C. with dies heated to from about 50 to 100° C. above the drawing temperature.

In testimony whereof we have hereunto set our hands.

ERNST DE RIDDER.
